Atty.

UNITED STATES PATENT OFFICE.

JAMES M. DODGE, OF CHICAGO, ILLINOIS.

DRIVE-CHAIN.

SPECIFICATION forming part of Letters Patent No. 241,944, dated May 24, 1881.

Application filed March 22, 1881. (Model.)

To all whom it may concern:

Be it known that I, JAMES M. DODGE, of Chicago, in the county of Cook and State of Illinois, have invented certain new and useful 5 Improvements in Drive-Chains; and I do hereby declare that the following is a full and exact description thereof, reference being had to the accompanying drawings, making part of this application.

10 My invention relates to certain new and useful improvements in what are known as "detachable drive-chains;" and it consists, first, in the combination, with a link-like device having two side bars, provided with cross-heads at 15 their free ends, and having the opposite ends of said side bars connected by a tubular end bar, of a pintle-like device adapted to fit and turn within said tubular end bar, and also adapted to engage at its projecting ends with the side 20 bars of a similar link-like device and to retain said side bars in engagement while the coupled parts maintain a working relative position, all as will be hereinafter more fully explained; 25 second, in the combination, with a link-like device formed of two side bars and one hollow end bar, and a pintle-like device having slotted ends and adapted to work in the said hollow end bar, as will be hereinafter described, of projections on the inner faces of the side 30 bars of said link-like device arranged near their free ends and adapted to perform the function of supplemental bearers against the pintle-like device of a similar link-like device, all as will be hereinafter more fully set forth.

35 To enable those skilled in the art to which my invention relates to make and use the same, I will now proceed to more fully explain it, referring by letters to the accompanying drawings, making part of this specification, and in 40 which I have illustrated my invention in the forms in which I have so far successfully practiced it.

Figure 1 is a face view of two of my improved links coupled together and in a working relative position. Fig. 2 is an edge view of the 45 same, (with the parts in the same relative position.) Fig. 3 is an edge view with the links turned out of their working position, and also showing one of the links slightly displaced. 50 Fig. 4 is a view looking at the contrivance seen at Fig. 3 from a point of view indicated by the

arrow in the last-mentioned figure, but showing the vertically-arranged link turned edge-wise, as it must be turned to effect the complete uncoupling of it from the other link. 55 Fig. 5 is a perspective view of the pintle-like device detached.

At Fig. 6 I have shown a modification of my invention, wherein the side bars of the link are so differently shaped that it may be disengaged from the slotted ends of the pintle-like device by simply first turning the parts in the relative position illustrated at Fig. 3, except that the turned-up link shall be still farther moved downward until the loop-like portions of the side bars shall coincide with the ends of the pintle-like device; while at Fig. 7 I have shown still another modification, in which, in lieu of having the ends of the pintle-like device slotted to accommodate the side 70 bars of the link, the latter are longitudinally grooved to accommodate tenons on the ends of the said pintles.

In the several figures the same part, wherever it occurs, will be found designated by the 75 same letter of reference.

In Figs. 1, 2, 3, 4, and 5, A A are the side bars, and B the one hollow end bar composing each 80 link-like device, and C are the pintle-like devices of the chain.

The free end of each side bar, A, is formed or provided with a sort of cross-head or enlargement at c^2 , and each of said side bars is also, by preference, provided at e with a projecting lug arranged on the inner face of the side bar and 85 near its free end, (for a purpose to be presently explained.)

The hollow end bar, B, is somewhat less in length than the extreme width of the link, as clearly shown, so that when two links are 90 coupled together their side bars, A, may come in line, as shown at Fig. 1, and said end bar, B, is preferably cut away slightly at two opposite points of each end, as shown at f , to facilitate the coupling and uncoupling of the parts 95 of the chain.

For the same purpose as that last mentioned, and also to facilitate the use of the supplemental lugs e , the pintle-like device C may be grooved longitudinally for a short distance from either 100 end; but to lighten this device I have made it grooved out its entire length, as shown at g .

(See Fig. 5.) This form gives it ample strength and proper wearing and bearing surfaces without unnecessary weight of stock. The slotted end portions of the pintle C are slabbed off, as shown at *i*, (see Fig. 5,) and by reference to Fig. 1 it will be seen that these portions *i*, which afford bearings for the cross-heads *c*², incline inwardly toward the axis of pintle C, from the outer ends of the portions *i* to the inner ends thereof. This inclination and a corresponding obliquity to the bearing surfaces of the cross-heads *c*² operates to make the free ends of the side bars, A, of each link in the chain draw together when the chain is under tensional strain, and thus avoids any possible weakening of the chain by a spreading of the free end of the three-sided links.

When the parts are united or coupled together and in any of the usual working relative positions, (as, for instance, that seen at Fig. 1,) the articulation of the parts will be perfect, and since the curved portions of the cross-heads *c*² abut against the shoulder-like portions *s* of the opposite link, the side bars, A, of one link cannot back out of the slotted end bearings of the pintle C of the next adjacent link; but by turning the links into the relation seen at Fig. 3, so that, as there illustrated, the side bars, A, may be moved longitudinally in the slotted ends of pintle C, the link capable of this movement may then be turned edgewise and moved bodily (as illustrated at Fig. 4) until it is entirely separated from its mate.

The lugs *e*, when employed, come to bearings against the bottom of groove *g*, near its ends, and act as a re-enforce, or as supplemental bearers to take the draft-strain conjointly with the cross-heads *c*² and bearing-surfaces at *i*.

In the modification shown at Fig. 6 the side bars, A, are incapable of separation from the slotted ends of the pintle C by any such turning movement relatively edgewise, as seen at Fig. 4, but are made with loop-like devices at *l*, so that by sliding the side bars, A A, along in the slotted pintle ends until the latter coincide with the loops *l*, the link may be moved away from the pintle ends in the manner obvious.

In the modification shown at Fig. 7 the pintle-like device C, in lieu of having slotted ends to accommodate the side bars, A, is formed with a tenon, *m*, which fits loosely in a groove, *o*, made in the inner face of the said side bar, and comes to a bearing at the root or end of said groove, against which, and in said tenon, the pulling strain comes. In this modification of the invention the parts of the chain are uncoupled and recoupled by substantially the same sort of movements of the said parts as in the case of that form of the invention shown at Fig. 1.

Having now sufficiently explained my invention and those modes in which I have so far practiced it to enable those skilled in the art to make and use detachable drive-chains embodying my improvements, and wishing it to be understood that I do not desire to limit the scope of my said invention to any precise forms or proportions of parts not essential to the novel principles of construction shown, what I claim as new, and desire to secure by Letters Patent, is—

1. In combination with a link-like device composed of two side bars, A A, and one hollow end bar, B, and having the free ends of its side bars formed or provided with projections, or their equivalents, as described, a pintle-like device, C, adapted to fit and turn in the tubular end bar, B, and to engage at its ends with the side bars of a duplicate link-like device, all substantially in the manner set forth. 75
2. In combination with a link-like device composed of two side bars and one hollow end bar, as described, and a pintle-like device, C, 85 slotted at its ends and grooved longitudinally near either end, the lug-like projections *e*, arranged on the inner faces of the side bars and adapted to bear against the bottom of said grooved portions of the pintle, as set forth. 90

In witness whereof I have hereunto set my hand this 2d day of March, 1881.

JAMES M. DODGE.

In presence of—

THOMAS KANE,
EPHRAIM BANNING.
